US0D1013521S

(12) **United States Design Patent** (10) Patent No.: **US D1,013,521 S**
(45) Date of Patent: ** Feb. 6, 2024

(54) **BOTTLE**

(71) Applicant: **H.J. Heinz Company Brands LLC**,
Pittsburgh, PA (US)

(72) Inventors: **Amy Adriana Wilhelmina Beekmans**,
Oirschot (NL); **Rudiney Ramos De Souza**, Cascais (PT); **Verónica Vanhackendover Salgueiro**, Cascais (PT)

(73) Assignee: **H.J. Heinz Company Brands LLC**,
Pittsburgh, PA (US)

(**) Term: **15 Years**

(21) Appl. No.: **29/777,842**

(22) Filed: **Apr. 8, 2021**

(51) LOC (14) Cl. **09-01**

(52) U.S. Cl. **USPC D9/549; D9/550**

(57) **CLAIM**

The ornamental design for a bottle, as shown and described.

DESCRIPTION

FIG. 1 is a top, front perspective view of a bottle showing our new design;

FIG. 2 is a bottom, rear perspective view thereof;

FIG. 3 is a left side elevation view thereof;

FIG. 4 is a right side elevation view thereof;

FIG. 5 is a rear elevation view thereof;

FIG. 6 is a front elevation view thereof;

FIG. 7 is a top plan view thereof; and,

FIG. 8 is a bottom plan view thereof.

The dash-dash lines in the drawings depict portions of the bottle that form no part of the claimed design. The dash-dot lines depict the boundaries of the bottle that form no part of the claimed design.
